DESIGN FOR AN ELECTRIC RAZOR

Henry J. Rand, New York, N. Y., and Wallace H. Nichols, Westfield, N. J., assignors to Remington Rand Inc., Buffalo, N. Y., a corporation of Delaware

Application November 5, 1938, Serial No. 80,902

Term of patent 14 years

To all whom it may concern:

Be it known that we, Henry J. Rand, a citizen of the United States and a resident of New York, in the county of New York, State of New York, and Wallace H. Nichols, a citizen of the United States and a resident of Westfield, in the county of Union, State of New Jersey, have invented a new, original, and ornamental Design for an Electric Razor, of which the following is a specification, reference being had to the accompanying drawing, forming part thereof.

In the drawing:

Fig. 1 is a rear elevational view of an electric razor showing our new design;
Fig. 2 is a side elevational view thereof;
Fig. 3 is a front elevational view thereof;
Fig. 4 is a plan view thereof.

We claim:

The ornamental design for an electric razor, as shown.

HENRY J. RAND.
WALLACE H. NICHOLS.
